UNITED STATES PATENT OFFICE.

JEAN MARIE BUISSON, OF BELMONT, FRANCE.

WIRE-DRAWING APPARATUS.

SPECIFICATION forming part of Letters Patent No. 309,688, dated December 23, 1884.

Application filed September 26, 1884. (No model.) Patented in France February 18, 1884, No. 160,389.

To all whom it may concern:

Be it known that I, JEAN MARIE BUISSON, a citizen of the French Republic, residing at Belmont, in said French Republic, have invented certain new and useful Improvements in Methods of and Machines for Drawing Wire, (for which I have obtained Letters Patent in France, No. 160,389, under date of February 18, 1884,) of which the following is a specification.

In the manufacture of wire, and more especially wire from ductile metals—such as soft iron, gold, silver, copper, &c.—it has been the custom to reduce the wire to the desired size by passing the same through a series of draw-plates, or through a draw-plate having a series of graduated reducing-eyes, the reduction being effected by successive operations of drawing, reeling, pickling, and lubricating.

The object of this invention is to diminish the labor connected with this mode of drawing wire by reducing the same at a single operation, the wire being drawn from the coarser to the finishing plate successively through all the intermediate plates.

The invention consists, essentially, in mechanisms and in combination of mechanisms for reducing wire to the proper thickness by a single operation by passing said wire through a series of draw-plates, maintaining the wire at the proper tension, and cooling the same on its passage from one draw-plate to the other, substantially as hereinafter described.

In the accompanying drawings, I have illustrated in Figure 1 by a perspective so much of a machine for drawing wire according to my process as will be necessary for the thorough understanding of the invention. Fig. 2 is an end elevation, showing the driving mechanism only.

The operative devices of the machine are supported by a suitable frame, in which said devices operate, and in which they have their bearings. The frame A, as shown, is composed of a table or platform, a, supported on uprights a', connected together by means of longitudinal girts a''. At the rear end of the table in suitable bearings is mounted the main driving-shaft b, driven from a suitable prime motor, and carrying a belt-pulley, B, belted

to a pulley, C², on a shaft, c, and a sprocket-wheel, B', connected by chain with a like wheel, C³, on said shaft c. The latter shaft also carries a second belt-pulley, C⁴, and sprocket-wheel C'.

Between the pulleys C² C⁴ on shaft c is mounted a conical pulley, C, belted with a like pulley, D, mounted on a shaft, d, near the platform of the machine, upon the belt d' of which pulley bears a brake-shoe, E, adjustable along the periphery of the said cone-pulley D in a slot, e, of a brake-lever, E', pivoted to the platform a of the frame A, or sliding in a guide-plate, e', as shown. The sprocket-wheel C² is connected by chain c² with a like wheel, F², on a shaft, f, that also carries a cone-pulley, F.

Between the cone-pulley F and the sprocket-wheel F² on shaft f is mounted a second sprocket-wheel, F', of smaller diameter than the sprocket-wheel F², connected by chain to a sprocket-wheel, G², on shaft g, which shaft also carries a cone-pulley, G, and between the cone-pulley and the sprocket-wheel G² is mounted a sprocket-wheel, G', of smaller diameter than the sprocket-wheel G².

It will be observed that the gearing shown and above described is so arranged as to drive the parts driven therefrom and herein described at a uniform speed, and that the speed of said parts relatively to and independently of each other may be varied by means of the cone-pulleys C F G, so that the speed of said parts may be gradually increased from the feed end to the delivery end of the machine. The cone-pulleys C F G are belted with like pulleys, H, I, and K, mounted on top or platform of the machine in suitable bearings. The shaft or journal h of the cone-pulley H carries the spool H' from which the wire is fed, the journal of the cone-pulley I carries a guide or speed pulley, I', and that of the pulley K a guide or speed pulley, K'.

On suitable standards are mounted disks, or, preferably, drums M, M', M'', &c., over which the wire passes and is cooled, and said drums may be kept cool by a circulation of cold water or other heat-absorbing medium fed thereto through one of their hollow standards and one of the hollow trunnions of the drums, said medium escaping from the drum

through the other hollow standard and trunnion in a well-known manner.

5 N N' are tension-pulleys mounted on levers n n', over which pulleys the wire is passed, and by which it is kept at the proper tension. Said levers n n' project through suitable openings in the platform and extend some distance below the same, said levers being pivoted in suitable bearings. (Not shown.)

10 S S' S² are hangers depending from the platform of the frame. They carry at their lower ends pulleys s s' s², respectively, over which passes a chain, wire, or cord, n³. One end of the cord n³ is attached to an arm, o', projecting from a rod, O, that is stepped in a bearing, o², at the foot of the frame, said rod O carrying at its upper end an arm, o, that has a locking-tooth, O', adapted to engage the notches or teeth of a sector-plate, O². The 15 wire, chain, or cord n³, attached to arm o', after passing around the pulley s on hanger S, passes around a like pulley, s', on hanger S', the opposite end of said cord being secured to the lower end of the rod n', or to an arm projecting therefrom. A cord that has a weight, p', attached thereto serves to hold the cord n³ at the tension at which it has been adjusted.

20 It is obvious that if any one of the tension-adjusting rods O is rotated in a given direction the arm o will either draw upon the cord n³ or slacken the same, thus moving the lever in one or the other direction to tighten or slacken the wire W, that passes around its tension-pulley at the upper end thereof.

25 35 Q Q' Q² are the draw-plates, the draw-eyes of which are successively of smaller diameter.

30 R R are belt-shifters for shifting the belts on the cone-pulleys C F G H I K to regulate the speed of the spool and the guide-pulleys H' I' 40 K', as will be readily understood. The wire W, wound on spool H', passes through the first draw-plate Q, thence over and around tension-pulley N, back again toward the spool, and over and around the cooling-drum M. From the 45 latter-drum said wire W passes around the guide or feed pulley I', from the feed-pulley the wire passes through the eye of the second draw-plate Q', thence around the tension-pulley N', back toward the feed-pulley I' over the 50 cooling-drum M'. From the latter drum the wire passes around feed-pulley K', then through the third draw-plate Q², around another tension-pulley, back toward feed-pulley K, and around cooling-drum M² to the next feed-pulley, and so on to and through the finishing or 55 last draw-plate, from which it passes to a spool on which the wire W, reduced to the desired thickness, is wound.

60 I have deemed it sufficient to show in the drawings but three draw-plates, the spool from which the wire is reeled, three tension and two feed-pulleys, and the devices necessary thereto to regulate the tension of the wire W, in order to illustrate the invention and render 65 the same intelligible to those conversant with this branch of manufactures. I would, how-

ever, have it understood that I do not confine myself to the number of the elements described, as it is obvious that they may be multiplied, and in fact, in practice, a greater number of 70 draw-plates are used, consequently a greater number of feed and tension devices.

To those conversant with this branch of manufactures the advantages of my invention will be readily understood, and I may state 75 that, aside from the great amount of labor and expense saved and the cleanliness of the work, the process of drawing wire has a further advantage, that the wire is not liable to become heated as in the old mode of drawing wire. 80 Furthermore, the wire being kept at a uniform tension by yielding tension devices, is not subjected to any sudden jerks due to an irregularity in the speed of the winding drum, or liable to any slack due to the speed of the feed- 85 drum.

The speed at which the wire is drawn through the draw-plates may be varied according to the nature of the metal. The drawing is effected slowly, and consequently without injury to the metal, each draw-plate having its own feeding devices, the speed of which may be regulated. Finally, a wire more pliable is obtained than can be obtained by the 90 old method of working.

95 Instead of driving the cone-pulleys C F G by sprocket-wheels and chains, they may be driven by belts or by toothed gearing.

Having thus described my said invention, what I claim as new, and desire to secure by 100 Letters Patent, is—

1. In a wire-drawing machine, the combination, substantially as herein described, of a series of draw-plates arranged successively, and having reducing-eyes of gradually-decreasing diameter from the feed toward the delivery end, feeding devices for feeding the wire to the plates, drawing-pulleys for drawing the wire through the plates, and tension-pulleys supported from weighted levers to maintain 105 the wire at the proper and at a yielding tension while passing from one draw-plate to the other, for the purposes specified.

2. In a wire-drawing machine, the combination, substantially as herein described, of a series of draw-plates arranged successively, and having reducing-eyes of gradually-decreasing diameter from the feed toward the delivery end, feeding devices for feeding the wire to the plates, and drawing-pulleys for drawing 110 the same through said plates, cooling-drums for cooling the wire, and tension-pulleys to maintain the wire at the proper tension while passing from one draw-plate to the other, for the purposes specified.

3. In a wire-drawing machine, the combination, substantially as herein described, of a series of draw-plates arranged successively, and having reducing-eyes of gradually-decreasing diameter from the feed toward the delivery end, feeding devices for feeding the wire to the plates, drawing-pulleys for drawing the 115 120 125 130

- same through said plates, and cooling-drums and tension-pulleys supported from pivoted weighted levers to cool the wire and maintain the same at the proper and with a yielding tension while passing from one draw-plate to the other, for the purposes specified.
4. In a wire-drawing machine, the combination, substantially as herein described, of a series of draw-plates arranged successively, and having reducing-eyes of gradually-decreasing diameter from the feed toward the delivery end, feeding devices for feeding the wire to the plates, drawing-pulleys for drawing the wire through the plates, tension-pulleys supported from one end of pivoted levers, and adjusting-pulleys operating upon the opposite end of said levers for regulating the tension of the wire and maintaining the same at a uniform but yielding tension, for the purposes specified.
5. In a wire-drawing machine, the combination, substantially as herein described, of a series of draw-plates arranged successively, and having reducing-eyes of gradually-decreasing diameter from the feed toward the delivery end, feeding devices for feeding the wire to the plates, drawing-pulleys for drawing the
- same through said plates, and driving mechanism consisting, essentially, of cone belt-pulleys and differential belt or chain gearing, whereby the speed of the drawing-pulleys may be regulated and varied, for the purposes specified.
6. The combination, substantially as herein described, with the pivoted rods or levers $n\ n'$, &c., carrying each a tension-pulley at their upper end, and a pulley, N^a , at their lower end, the hangers P , and their pulleys P' , of the rod O and the cord n^b , said parts being arranged for operation as and for the purposes set forth.
7. The combination, with the shaft c , the cone-pulley C , the cone-pulley H , and the cone-pulley D , connected as described, of the brake $E\ E'$, said parts being arranged substantially as and for the purposes specified.

In testimony that I claim the foregoing I have hereunto set my hand this 23d day of May, 1884.

JEAN MARIE BUISSON.
